UNITED STATES PATENT OFFICE.

MONROE WILCOX AND BIGE WILCOX, CASSADAGA, NEW YORK.

WASH-BENCH.

SPECIFICATION forming part of Letters Patent No. 363,104, dated May 17, 1887.

Application filed February 8, 1886. Serial No. 191,214. (Model.)

To all whom it may concern:

Be it known that we, MONROE WILCOX and BIGE WILCOX, citizens of the United States, residing at Cassadaga, in the county of Chautauqua and State of New York, have invented 5 a new and useful Improvement in Wash-Benches, of which the following is a specification, reference being had to the accompanying drawings.

Our invention relates to improvements in 10 wash-benches; and it consists of the peculiar combination and novel construction and arrangement of the various parts for service, substantially as hereinafter fully set forth, and 15 particularly pointed out in the claims.

The object of our invention is to provide an 20 improved wash-bench with foldable frames for supporting the tubs, which are so constructed and arranged that the pivots are relieved of the weight and strain of the tubs and their 25 contents when the frames are unfolded and adjusted for use, thereby very materially increasing the strength and durability of the apparatus.

A further object of our invention is to provide 30 foldable frames or benches for the tubs, which shall be retained or held in their folded position against the central frame by frictional contact therewith, and dispense with independent fastening devices which require to be manipulated by hand.

Referring to the drawings, which illustrate 35 a wash-bench embodying our invention, Figure 1 is a top plan view of the bench unfolded and adjusted for use. Fig. 2 is a side elevation corresponding to Fig. 1, showing the tubs in dotted lines on the folding frames or benches. Fig. 3 is a vertical longitudinal central sectional view on the line $x-x$ of Fig. 1. Fig. 4 40 is a perspective view of the bench in its folded position. Fig. 5 is an elevation taken from one end of the apparatus in the position shown in Fig. 4. Fig. 6 is a detached perspective view of the soap-shelf and its suspending hook.

Referring to the drawings, in which like 45 letters of reference indicate corresponding parts in all the figures, A designates the central self-supporting frame, which comprises the uprights or posts A', arranged parallel 50 with each other, and the transverse rails or bars a², a³, and a⁴, which are rigidly and firmly secured to the uprights to brace and strengthen them. The uprights of the central frame are recessed on one side to provide vertical ex-

tended flanges a⁵ at their upper ends, to which 55 are secured the transverse rail a⁶, and the rails a² a³ are secured to the uprights on opposite sides and at different heights, for a purpose hereinafter explained.

B and B' designate the folding frames or 60 benches, which are arranged on opposite sides of the central frame, and which fold independently of each other. Each of these frames or benches consists of the side rails or bars, b, and the folding legs b², which are pivoted to 65 the outer or free ends of the side rails, b, as shown. The side rails of the frames or benches are arranged outside of or exterior to the uprights of the central frame, A, and are pivoted to said uprights at their inner ends, as at b', 70 and the folding legs b² for the benches are arranged exterior to the bars b thereof. When the frames or benches are folded for the purpose of storing and transporting the apparatus, the side bars, b, bear against the outer faces of 75 the uprights of the central frame, and the legs b² are arranged in like manner to the side rails, b—i. e., against their outer faces. The rails of the benches or frame bind against the central frame, A, and the legs bind against the 80 side bars of the frame or benches, so that the bench and its legs are held in their folded position by frictional contact with the central frame, A, without employing independent fastening devices. The benches fold against 85 the outside faces of the uprights of the central frame, so that the rails and legs lie wholly within the edges of the uprights, and are thereby protected from injury to a considerable extent, and by reason of the peculiar arrangement of parts just described the apparatus folds very compactly, so that it takes up but little room, which is very desirable in 90 storing and transporting them.

The legs b² of the benches have secured to 95 them, near their upper ends, transverse rails b³, which connect the two legs of each bench and cause them to move simultaneously. These rails b³ are arranged beneath the outer free ends of the side rails of the benches when the latter are unfolded, so that the said side rails can bear and rest thereon. The benches B B' are pivoted to the central frame, A, at different heights or elevations, so that persons of different heights can use the apparatus very 100 conveniently, and when the benches are unfolded the inner ends of the side rails, b, thereof 105 rest on the upper edges of one of the rails a².

or a^3 , the rail a^2 being secured to the central frame at the side on which the bench B is arranged, and the rail a^3 on the opposite side of the said central frame to adapt the rails of the bench B' to bear or rest thereon. We lay special stress on the peculiar arrangement of the bars or rails a^2 a^3 and to the rails b^3 with relation to the folding frames or benches and their legs, as by such construction and arrangement the pivots of the benches and their legs are relieved of the weight and strain of the tubs and their contents when the apparatus is in use, thereby greatly increasing the rigidity, strength, and durability of the same without increasing the cost of manufacturing it.

It will be observed that the folding benches or tub-supports are mere skeleton frames, consisting of parallel side rails, b b , and the transverse connecting-rail b , and it is therefore necessary to select tubs or like receptacles of a diameter equal to or greater than the width of the said benches for use thereon, so that the lower edges of the tubs will rest or bear firmly upon the parallel side bars of the benches, as will be very readily understood by reference to Figs. 1 and 2 of the drawings.

C designates a swinging reversible deflector, which is pivotally supported on pins c , near the upper ends, and between the standards or uprights of the central frame, A, so that it can be turned or inclined into different positions to direct the water falling thereon from a wringer above into either one or the other of the tubs or like receptacles supported on the frames or benches; but we lay no claim herein to the reversible deflector, as we are aware that substantially the same device has been heretofore used for the same purpose.

A wringing apparatus of any approved pattern can be detachably connected to the upper transverse rail, a^4 , of the central self-supporting frame, A, as indicated in dotted lines in Fig. 2, for the purpose of wringing the clothing or fabrics after they have been washed; but when the fabrics are being washed it is preferred that the wringer shall be replaced by a shelf, D, which serves to hold the soap used in washing the fabrics, so that there will be no danger of the soap falling into the water in the tub and be thereby wasted, as is very often the case. This shelf D is arranged between the upper ends of the standards of the central frame and in an inclined position, so that its lower edge bears against the transverse rail a^4 , and its opposite or free edge is elevated or held in a higher position, whereby the soap or other article that is placed on the said shelf will not be liable to slip off the shelf and fall accidentally. The shelf is detachably suspended from the rail a^4 of the central frame by means of a hook or bracket, d, which is bent from a single piece of wire for the purpose of cheapness in the manufacture. The said hook or bracket comprises the parallel side arms or bars, d , the angular prongs or teeth d^2 at the lower free ends of the said arms, and the curved arm d^3 , connecting the said side arms at the ends opposite

the prongs, and having its middle depressed below and arranged to one side or out of line with the side arms, to constitute the hook. 70 The prongs enter the inclined shelf at one of the sides thereof to firmly and rigidly secure the bracket to the shelf, and the hook of the bracket takes over the transverse rail a^4 , while the side arms bear against the rail a^4 . 75

By means of the bracket the shelf can be readily and easily applied to and disconnected from the rail a^4 of the central frame, A, and the side arms of the bracket bear against the rail a^4 , to prevent the shelf from moving and support it very firmly and steadily in place. 80

The operation of our invention will be readily understood from the foregoing description, taken in connection with the drawings. 85

We are aware that wash-benches have been heretofore provided which consist of a self-supporting standard adapted to receive a wringer, and folding frames hinged to the central standard having swinging legs to fold against the outer rails of the benches, which are held in their folded positions by pivoted catches or other locking devices, as such devices are not new; and hence we confine ourselves to the peculiar arrangement and construction of parts hereinafter claimed. 95

Having thus described our invention, we claim—

1. The combination of a central frame, the cross-rails a^2 a^3 , affixed thereto on opposite sides, the folding benches or frames pivoted to the central frame, and having their inner ends connected to said frame above the transverse rails thereon, the legs pivoted to the outer free ends of the folding benches, and 100 the transverse rails affixed to the legs beneath the free ends of the benches, whereby the side rails of the benches are adapted to bear and rest on the transverse rails and relieve the pivots of the benches and legs of 105 the weight and strain of the tubs, as set forth.

2. In a portable wash-bench, the combination of a central self-supporting frame, A, provided with the cross rails or bars a^2 a^3 on opposite sides, the folding benches arranged 115 on the outside of the central frame and pivoted at their inner ends to the central frame to fold against the outer sides thereof, and the swinging legs carrying a connecting-bar, b , near their upper ends, and arranged on 120 the outside of the benches and pivoted thereto to fold against the outer sides of the benches, whereby the benches bind upon the central frame and the legs bind upon the benches when the parts are folded, substantially as described, for the purpose set forth. 125

In testimony that we claim the foregoing as our own we have hereto affixed our signatures in presence of two witnesses.

MONROE WILCOX.
BIGE WILCOX.
